UNITED STATES PATENT OFFICE.

SYDNEY ELLIOTT PAGE, OF LONDON, ENGLAND.

SCORING DEVICE.

1,086,077.

Specification of Letters Patent.

Patented Feb. 3, 1914.

Application filed August 30, 1912. Serial No. 717,839.

To all whom it may concern:

Be it known that I, SYDNEY ELLIOTT PAGE, a subject of the King of Great Britain, residing at London, England, have invented 5 certain new and useful Improvements in Scoring Devices, of which the following is a specification.

My invention relates to improvements in scoring devices, more especially for attachment to a card table for scoring the points 10 in games of cards such as bridge, dominoes, and the like.

The objects of my improvement are, firstly to provide a writing surface which shall 15 be as nearly flush with the table surface as possible; and secondly to attach the said surface to the table in such a way that it may always be at hand when wanted. I attain these objects by the mechanism illustrated in 20 the accompanying drawings, in which:—

Figure 1 represents the invention embodied in a detachable device with a clamping plate and screws; Fig. 2 shows a detachable device with a clamping plate and spring 25 hinge; and Fig. 3 is an end view of Fig. 2 with the paper removed.

The device is intended primarily for detachable connection with a card table a portion 30 of which is indicated at *t*, but may be used with any table.

Fig. 1 shows one form of the detachable scorer. The writing surface *a* in this case is bent around the edge of the table and terminates as a clamping plate having extensions *c* through which pass clamping screws *d* by which the surface is firmly secured to a 35 table or other support. The paper box *e* is formed with the extended flexible side *h* and the flange *f* which coöperating with the catches *g* removably secure the box to the clamping plate; the ridges *i* provide a paper space between the side *h* and the plate *a*. The end plate *k* is flexibly secured, or it may 40 preferably be formed with a spring hinge, so that the paper may be thereby held while being torn off against the sharp edge *x*. Referring to Figs. 2 and 3, the writing surface *a* has the flap *b* connected by a spring hinge *p* at one of its long sides, and the writing 45 surface has the long edges overturned, on the right-hand side to form a guiding ridge and on the left-hand side to form the hinge and a guiding ridge; the paper fits accurately in the recess formed by the overturned 50 edges and a corresponding dip in the cross bars of the flap *b* further serves to hold the

paper *o* steady. The clamping plate *s* is formed integrally with the brackets *v* and with a serrated edge which is pressed against the underside of the table by the action of the spring hinge *r* formed with a spring 60 strong enough to give a satisfactory grip to hold the plate *a*. Overturned parts *q* guide the paper over the bent down portion. In order that the paper roll shall not unwind 65 when not required, spring strips or tongues *l* are formed within the bracket *v* which press against the edges of the paper roll and prevent it turning owing to the friction set up. In certain cases where but little 70 room is available the brackets *v* can be so hinged to the clamping plate that they can be pressed with the paper roll somewhat beyond the edge of the table when the folding legs thereof are up, but may fall back 75 beyond the edge when the legs are down so that the table may be put away on its edge without damaging the scorer. It will be seen that by providing lugs on the bent down portions of the surface *a* the device could 80 readily be attached to the table by ordinary screws passing through the beading strip *y*.

In any of the figures the space *n* may be provided stamped with the score points of any particular game. The paper may be 85 ruled to suit the game in which it is used and the rolls of paper may readily be changed by springing them into the brackets *v*, where they may be prevented from too free rotation by the springs *l*, struck up 90 from the metal of brackets *v*.

In Fig. 2, the bar *m* is to represent the division line used for the game of "bridge". Having finished a score, the flap *b* is raised, the paper *o* pulled along and the used part 95 cut off against the fine edge *x* of the flap *b*.

What I claim and desire to secure by Letters Patent is:—

1. The combination, in a table attachment for scoring and the like, of a thin body portion having a downward addition and having overturned lateral edges for guiding a strip of paper from a roll, a flap having a transverse tearing edge thereon, a spring-controlled hinge connecting the said flap 100 and the body portion so that the flap normally presses down on the latter, a clamping plate attached to said downward addition and projecting longitudinally underneath the end of the body portion to an extent not appreciably greater than the size 105 of a full roll of paper, means for connecting 110

the clamping plate with the under surface of a table so that the said body portion may be thereby removably secured to single table edges of varying thickness wholly from one end, and means for rotatably securing a single roll of paper on said clamping plate.

2. The combination, in a table attachment for scoring and the like, of a thin body portion having a downward addition and having overturned lateral edges for guiding a strip of paper from a roll, a cutting-off edge flexibly secured to and supported transversely the body portion, a clamping plate projecting longitudinally underneath the end of the body portion to an extent not appreciably greater than the size of a full roll of paper, a spring-controlled hinge between the said clamping plate and the extremity of said downward addition, and means for rotatably securing a single roll of paper on said clamping plate.

3. The combination, in a table attachment for scoring and the like, of a thin body portion having a downward addition and having overturned lateral edges for guiding a strip of paper from a roll thereof, a flap having a transverse tearing edge thereon, a spring-controlled hinge connecting the said flap and the body portion so that the flap normally presses down on the latter, a clamping plate projecting longitudinally underneath the end of the said body portion to an extent not appreciably greater than the size of a full roll of paper, a spring-controlled hinge between the said clamping plate and the extremity of said downward addition, and means for rotatably securing a single roll of paper on said clamping plate.

4. The combination, in a table attachment for scoring and the like, of a thin body por-

tion having a downward addition and having overturned lateral edges for guiding a strip of paper from a roll, an open flap having a transverse tearing-edge along its top edge and having depressed cross-bars, a spring-controlled hinge connecting the said flap and the body portion, a clamping plate projecting longitudinally underneath the end of the said body portion to an extent not appreciably greater than the size of a full roll of paper, a spring-controlled hinge between said clamping plate and the extremity of said downward addition, and means for rotatably securing a single roll of paper on said clamping plate.

5. The combination, in a table attachment for scoring and the like, of a thin body portion having a downward addition and having overturned lateral edges for guiding a strip of paper from a roll thereof, a cutting edge flexibly secured to and supported transversely of the body portion, a clamping plate projecting longitudinally underneath the end of the body portion to an extent not appreciably greater than the size of a full roll of paper, a spring-controlled hinge between said clamping plate and the extremity of said downward addition, and flexible brackets attached to the said clamping plate and having pivots for entering the hollow center of a single paper roll and having flexible tongues or strips bearing against the paper roll, all substantially as described herein.

75
In testimony whereof I affix my signature in presence of two witnesses.

SYDNEY ELLIOTT PAGE.
